UNITED STATES PATENT OFFICE

2,406,814

TRESTLE BRIDGE

James A. Dorst, United States Army,
Geiger Field, Wash.

Application December 17, 1943, Serial No. 514,613

2 Claims. (Cl. 14—1)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to a bridge and the primary object thereof is to provide a device of this character having prefabricated parts which may be readily transported to a body of water and speedily erected for facilitating the passing of vehicles and the like thereover and quickly knocked down for transportation and assembly at other places.

Another object of the invention is to provide a bridge structure of few parts, which may be easily replaced or speedily repaired upon being damaged, quickly modified to carry heavy loads and the parts may be assembled together in such a manner as to form a unitary bridge structure without substantially any noise.

The invention is directed more particularly to a trestle bridge for use by army engineers in spanning bodies of water whereby vehicles may pass over the same and briefly comprises longitudinally extending spaced treadways and guide rails supported on bents including transversely extending transoms vertically adjustably mounted thereon, with each of the treadways being made of a plurality of sections of spaced stringers overlapping at their ends, and having filler blocks therebetween, said stringers and guide rails being detachably secured together by clamps.

With the above and other objects and advantages in view the invention consists of certain features of construction and operation of parts which will hereinafter be shown in the accompanying drawings in which:

Fig. 1 is a fragmentary side elevation of the improved bridge;

Fig. 2 is a top plan view thereof;

Fig. 3 is a cross sectional view taken on line 3—3 of Fig. 2;

Fig. 4 is a detail view of a clamp member and knee brace used in carrying out the invention; and

Fig. 5 is a top plan view thereof.

Referring more particularly to the drawings the improved bridge comprises a structure of suitably spaced trestle bents indicated generally by A, with each bent including a pair of vertically extending uprights or trestle columns 1 and a transom or horizontally extending beam 2 adjustably mounted thereon. The uprights or trestle columns 1 are each formed of a pair of parallel bars 1' held in spaced relation by blocks 3 and having mud shoes or footings 4 on their lower

2

ends, which mud shoes or footings 4 are adapted to engage the bottom 5 of a river bed or the like. The ends of the transoms 2 extend between the pairs of spaced trestle bars 1' and are supported on cross pieces 6 mounted between friction blocks 7 of clamp members indicated generally by 8. The clamp members 8 also include friction blocks 9 pivotally connected through the links 10 and the bolt 11 by staples 11a to the friction blocks 7.

The bents A are provided with knee braces 12 having side members 13 mounted on their upper ends, which side members 13 engage opposite sides of the transoms 2 and are secured thereto by bolts 14. The upper ends of the knee braces 12 abut against the lower edges 15 of the transoms 2 and the lower ends of the knee braces are secured by bolts 16a or other suitable means to the lower ends of the friction blocks 7. Strap members 17 secured to the friction blocks 7 by means of bolts 16 are adapted to engage detachably the trestle columns 1. The lower ends of the braces 12 extend between the pairs of spaced bars 1' forming the trestle columns 1. The transoms 2 support dual suitably spaced treadways indicated generally by B, with each treadway consisting of a plurality of sections 18 of longitudinally extending stringers 19 seated at their bottom edges on the transoms 2. The stringers 19 of each treadway are in suitable spaced relation and are of sufficient length to more than span the bents A. The ends of one section 18 of stringers 19 extend between the ends of another section of stringers or in other words the ends of one section of stringers 19 overlap the ends of an adjacent section of stringers. Filler or spacer blocks 20 are provided between the stringers 19 at mid-span and guide rails 21 are provided, said guide rails 21 being of a greater height than the stringers 19 and are positioned adjacent the innermost stringer of each treadway.

The stringers 19 and guide rails 21 are detachably secured together by means of suitably spaced clamps 22, each consisting of a pair of bolts 23 having end plates 24 mounted thereon, said clamps 22 being arranged in a vertical plane with the bolts 23 extending horizontally across the stringers 19 and through the guide rails 21.

The upper ends of the trestle columns 1 of the bents A are provided with grooves 25 which are engaged by safety ropes or cables 26 secured to the friction blocks 9 and safety ropes or cables 26' are attached to the ends of the transoms 2 and to the upper ends of the trestle columns 1. The safety ropes or cables may be attached only to the transoms 2 and the upper ends of the tres-

tle columns 1 if desired. Ropes or cables 27 also connect the trestle columns 1 on the bents A together in a manner as to provide cross bracing for the bridge structure.

The bridge structure above-described can be transported by trucks of normal size to a river or other body of water to be crossed and upon the trucks reaching the selected place, the bents A are positioned therein with the mud shoes or floorings 4 engaging the bottom 5 of the river bed. The clamp members 8 are moved vertically upward on the trestle columns 1 to the desired height by means of safety ropes 26 while the strap members 17 engage the trestle columns 1 and serve as guides. The transoms 2 and the roadway B are then placed in position with the transoms 2 supporting the roadway B and resting on the crosspieces 6 and the knee braces 12. The weight of the transoms and the roadway acting on the crosspieces 6 tend to force the blocks 7 downwardly and by means of the links 10 cause the blocks 7 and 9 to grip the trestle columns 1 tightly. After the transoms 2 have been placed in position and the roadway B mounted thereon, the stringers 19 and the guide rails 21 are detachably secured together by the clamps 22, after which the cross bracing ropes or cables 27 are secured to the trestle columns 1 as illustrated in Fig. 1.

By placing the filler blocks 20 between the stringers 19 at substantially mid-span the utmost efficiency results. There is no flooring used on the stringers 19, as the upper edges thereof serve that purpose and with this arrangement of the stringers to form the treadways a certain degree of continuous-beam action is provided, thereby insuring a better lengthwise distribution of a load than if this action were lacking.

The bridge is designed to have a minimum weight per linear foot and is formed of parts limited to predetermined lengths, whereby they may be easily transported from one place to another. The parts of the bridge are also individually buoyant and small in size, hence require no excessive weights for submergence or pass beyond the man handling range at any time. For

short stretches of deep water the bridge may be erected from one end only at a predetermined number of feet per hour and the longer the crossing the faster the speed of assembly, as the bridge may be then erected from any suitable number of ends. The bridge may also be easily and simply modified to carry heavy loads by halving the span between bents having a certain number of extra trestle columns added thereto.

10 If desired, the stringers 19 may be laid on transoms mounted on pontoons in providing a span across a body of water.

It will thus be seen that there is provided a novel and useful form of bridge structure which 15 is well adapted for the purpose intended. Even though there has herein been shown certain features of construction and operation of parts, it is nevertheless to be understood that various changes may be made therein, if the changes do 20 not depart from the spirit or scope of the claims.

Having thus described my invention, what I 25 claim as new and wish to secure by Letters Patent is:

1. In a bridge structure of the class wherein 30 a roadway is supported by a vertically adjustable transom arranged transversely between a pair of trestle columns positioned at opposite sides of said roadway, the combination with a trestle column and a transom, of a vertically adjustable transom support comprising a pair of friction blocks slidably disposed on opposite sides of said trestle column, one of said friction blocks being adapted to support said transom, suspension means for supporting the other friction block at 35 a predetermined point on said trestle column and link means pivotally connecting said friction blocks, said link means being operably responsive to the weight of said transom on said transom supporting friction block for clamping each 40 of said friction blocks on said trestle column.

2. A bridge structure as set forth in claim 1 characterized in that one of said friction blocks is provided with a knee brace adapted to engage 45 said transom.

JAMES A. DORST.
